CLAIM

The ornamental design for an add-on for a smartphone for smartphone-based photorefraction, as shown and described.

DESCRIPTION

FIG. 1 is a front perspective view of an add-on for a smartphone for smartphone-based photorefraction;

FIG. 2 is a left side view thereof;

FIG. 3 is a right side view thereof;

FIG. 4 is a rear view thereof;

FIG. 5 is a front plan view thereof;

FIG. 6 is a top view thereof;

FIG. 7 is a bottom view thereof; and,

FIG. 8 is a rear elevation perspective view thereof.

The broken lines depict portions of the smartphone in which the design is embodied that form no part of the claimed design.

1 Claim, 5 Drawing Sheets
